UNDERFEED STOKER, INCLUDING COOLED
TUYERE MEANS

Frank L. Kyger, Streator, Ill.

Application April 23, 1948, Serial No. 22,839

4 Claims. (Cl. 110—44)

1

This invention relates to a stoker retort and has for one of its objects the production of a simple and efficient retort which will efficiently burn a poor grade of coal, such as "bug dust" and cause this poor grade of coal to burn evenly and thoroughly and to also clinker perfectly.

A further object of this invention is the production of a simple and efficient tuyère for supplying air currents to the firebox on either side of the retort to facilitate a maximum combustion.

Other objects and advantages of this invention will appear throughout the following specification and claims.

In the drawings—

Figure 1 is a top plan view of a furnace and the retort, the top or cap of the furnace being removed;

Figure 2 is a side elevational view of the retort and stoker, certain portions being shown in section, and a portion of the furnace being shown in dotted lines;

Figure 3 is an enlarged irregular sectional view taken on line 3—3 of Figure 1 looking toward the hopper, the tuyères being shown in elevation;

Figure 4 is an enlarged sectional view taken on line 4—4 of Figure 1 looking from the hopper toward the retort;

Figure 5 is a central longitudinal sectional view of the retort and a portion of coal tube and conveyor;

Figure 6 is an enlarged vertical sectional view of one of the tuyères;

Figure 7 is a horizontal sectional view taken on line 7—7 of Figure 6 the support being eliminated;

Figure 8 is a front elevational view of the detached baffle-plate which is mounted in the casing of each tuyère;

Figure 9 is a fragmentary vertical sectional view of one of the tuyères and a portion of the fuel feeding trough.

By referring to the drawings, it will be seen that 10 designates a conventional furnace of any suitable type in which the retort 11 is mounted. The retort is provided with an upwardly inclined bottom 12, below which is located the wind box 13. The wind box 13 is supplied with a suitable draft through the medium of the air tube 14 which communicates with the wind box 13 at the front end thereof. Fuel is fed from the hopper 15 through the coal tube 16 by means of a conventional spiral conveyor 17. The inner end of the coal tube 16 preferably passes through the casing 18 which forms a junction with the retort

2

11. The bottom 12 is inclined upwardly and rearwardly from the bottom of the conveyor 17 to the inner end of the retort to an elevation substantially in line with the longitudinal axis of the conveyor 17, as shown in Figure 5. The casing 18 and the wind box 13 which carries the retort 11, is supported upon suitable supporting legs 19. A suitable cover plate 20 is anchored upon the casing 18 and the inner end of the coal tube 16 is anchored by means of a screw 21 to the cover-plate 20, which plate is shaped to fit the tube 16 as shown in Figure 4. The tube 16 and spiral conveyor 17 terminate at the mouth 22 of the retort 11, as shown in Figure 5.

15 The retort 11 is provided with the inclined bottom 12 defining an inclined trough 23 and having upwardly and laterally diverging side walls 24 which walls 24 terminate in laterally extending horizontal side ledges 25. These ledges 25 are provided with a plurality of aligned apertured sockets 26 defining communicating ports which communicate with the interior of the wind box 13 upon opposite sides of trough 23. A tuyère or tuyère section 27 is fitted at its lower end in each 20 socket, thereby defining a row of upright tuyères 27 to either side of the trough 23 upon the ledges 25. Longitudinally extending angle anchoring plates 28 are secured to the ledges 25 and are vertically channelled as at 29, to receive the tuyères 27. The tuyères 27 are anchored in the channels 29 by means of suitable anchoring screws 30.

25 Each tuyère 27 comprises a substantially vertical hollow cylinder having a closed top 31 and an open bottom 32, which open bottom communicates with the apertured socket 26 in which it is mounted. The rear portion 33 of each tuyère is reduced in its transverse diameter to snugly fit into the channel 29 of the anchoring plate 28 which is adapted to receive the same. The front face 34 of each tuyère is provided with a plurality of vertically spaced horizontal slots 35 which extend approximately one-half the diameter of the tuyère, or around the front face or half thereof so that the slots 35 will face in the direction of the trough 23. The tuyères upon opposite sides of the trough 23 face each other as shown. The front half of the transverse diameter of the tuyère is enlarged relative to the rear portion 33, as shown in Figure 7, thereby defining a pair of vertical ledges 36 at the junction of the rear portion 33 and front half of the tuyère. A central bracing web 37 is preferably located intermediate the ends of each slot 35 to reinforce the tuyère between the slots. The upper and lower walls 38 and 39 of each slot 35

preferably diverge outwardly to tend to prevent the clogging of the slots and the air blast passing therethrough will also tend to dislodge any clogging ashes, fuel, or the like.

A removable baffle-plate 40 is fitted into each tuyère 27 inwardly of the air slots 35, as shown in Figures 6 and 7. This plate 40 is substantially semi-circular in cross section and is provided with a plurality of vertically spaced horizontal slots 41 which are arranged in staggered vertical relation with respect to the slots 35, as shown in Figure 6. A spacing flange 42 is located below each slot 41 and a spacing flange 43 is located in spaced relation from the top 44 of the baffle-plate 40. The flanges 42 and 43 abut the inner face of the casing of the tuyère 27 just below the slots 35 to space the baffle walls 45 from the apertures 35, as shown in Figure 6. This arrangement locates the baffle walls 45 in inwardly spaced relation to the slots 35 and causes the air from the wind box 13 to pass in an irregular path through the tuyère. The air will enter the bottom of each tuyère and pass inwardly of the baffle-plate 40, out through the slots 41, downwardly and then out through the slots 35. Air will also pass over the top 44 of the plate 40 and out through the top slot 35. The bottom feet 46 rest upon the upper face 26^a of the ledge 25 which supports the tuyère to hold the plate in a proper position.

The operation of the retort is as follows:

Coal is fed into the trough 23 by the conveyor and is moved up the inclined bottom 12 in the direction of the arrows shown in Figures 1 and 5, toward the rear end of the retort. Air passes from the wind box 13 up through the apertured sockets 26 vertically through the tuyères 27 over the baffle walls 45 then downwardly of these walls, and out through the slots 35 and over and through the coal which moves upwardly of the inclined bottom 12. Since the tuyères 27 are located at opposite sides of the trough 23, with the draft discharge slots 35 facing in a direction to discharge the air transversely across the trough 23 and coal therein, the combustion of the fuel will be greatly facilitated. Consequently, a very low grade of coal may be burned and a maximum heat obtained therefrom because of the fact that the draft is distributed across the entire transverse area, and over the entire length of the trough 23, thereby assuring the complete burning of the fuel and avoiding waste as well as delay which otherwise would be necessary in removing unburned fuel.

It is a well known fact that a low grade coal such as "bug dust" will not burn with a natural draft nor in a regular or conventional stoker retort, because of lack of proper draft and the clogging of the retort by coke trees and the like, which form therein. With the present construction this difficulty is avoided.

It will be noted that since the bottom of the trough is inclined upwardly and away from the conveyor the fuel will be elevated gradually in proportion to the distance which the fuel travels within the trough and away from the conveyor.

It should be understood that since air enters the combustion chamber on opposite sides throughout the length of the retort, the incoming coal reduces air pressure on the coal at the entrance and increases air pressure as the coal pushes past and over the tuyères. This action permits the use of a large volume of air at all times to produce maximum combustion. The coal is spread evenly over the combustion

chamber and is pushed forwardly and upwardly on the inclined bottom, thereby producing a wedge-like action or formation of coal, to prevent blow holes and also to prevent packing of the coal against the tuyères. The fact that the coal moves longitudinally of the retort up an incline facilitates this operation.

It should be understood that clinkers in the fire-box may be removed with conventional clinker tongs, and any desired type of ash removing mechanism may be employed. The ash removing means forms no part of this invention. A grate G of a conventional type may be used and an ash wiper, gear box and vacuum nozzle of the conventional type, may be used therewith.

By considering Figure 9, it will be noted that the fine coal and ashes work up the sloping wall of the trough 23 and vertically of the tuyères, but the vertical walls 45 of the baffle plate 40 prevent the fine coal and ashes from entering the slots 41, since this fine material will not climb the vertical walls 45 against the pressure of the air from the wind box passing through the tuyères.

It should be noted that the spaced tuyère sections 27 extend vertically of the retort and that the slots 35 provide radial draft discharge openings for discharging a draft transversely of the trough and also transversely across the intervals between the spaced tuyère sections to set up a wall of air along each side of the trough for preventing the overheating of the tuyère sections. Furthermore, each tuyère section is individually anchored within a vertical channel 29 of the anchoring plates 28 to facilitate replacement of one section independent of the other sections, and the inner face of each tuyère section is curved transversely defining spaced rounded abutments along opposite sides of the trough.

Having described the invention, what is claimed is:

1. A stoker comprising a coal feeding means, a trough for receiving the coal from the feeding means, a series of vertical draft discharge tuyère sections located upon opposite sides of the trough at spaced intervals, and each tuyère section having radial draft discharge openings for discharging a draft transversely of the trough and also transversely across the intervals between the spaced tuyère sections to thereby set up a wall of air along each side of the trough for preventing the overheating of the tuyère sections.

2. A stoker comprising a coal feeding means, a trough for receiving the coal from the feeding means, a series of vertical draft discharge tuyère sections located upon opposite sides of the trough at spaced intervals, each tuyère section having radial draft discharge openings for discharging a draft transversely of the trough and also transversely across the intervals between the spaced tuyère sections to thereby set up a wall of air along each side of the trough for preventing the overheating of the tuyère sections, and means for individually anchoring each tuyère section in place to facilitate replacement of each tuyère section independently of the other sections.

3. A stoker comprising a coal feeding means, a trough for receiving the coal from the feeding means, a series of vertical draft discharge tuyère sections located upon opposite sides of the trough at spaced intervals, each tuyère section having radial draft discharge openings for discharging a draft transversely of the trough and also transversely across the intervals between the spaced

tuyère sections to thereby set up a wall of air along each side of the trough for preventing the overheating of the tuyère sections, each tuyère section having a curved inner face extending transversely thereof defining a plurality of vertical spaced rounded abutments along opposite sides of the trough.

4. A stoker comprising a coal feeding means, a trough for receiving the coal from the feeding means, a series of vertical draft discharge tuyère sections located upon opposite sides of the trough at spaced intervals, each tuyère section having radial draft discharge openings for discharging a draft transversely of the trough and also transversely across the intervals between the spaced tuyère sections to thereby set up a wall of air along each side of the trough for preventing the overheating of the tuyère sections, said trough having laterally extending ledge portions, anchoring plates carried by said ledge portions, said anchoring plates having spaced vertical channels, receiving said tuyère sections, and means

for removably anchoring said tuyère sections in said channels to facilitate replacement of the individual tuyère sections.
